The ornamental design for an electronic coffee scale as shown and described.

DESCRIPTION

FIG. 1 is a front, right and top perspective view of an electronic coffee scale, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the electronic coffee scale that form no part of the claimed design. The oblique surface shade lines shown in the drawings indicates a transparent surface.
